[57] CLAIM

The ornamental design for a female hygiene apparatus, as shown and described.

DESCRIPTION

FIG. 1 is a perspective view of the front, left and top of my

new female hygiene apparatus;

FIG. 2 is a front end elevational view of the apparatus;

FIG. 3 is a rear elevational view;

FIG. 4 is a top plan view;

FIG. 5 is a bottom plan view;

FIG. 6 is a left side elevational view;

FIG. 7 is a right side elevational view; and,

FIG. 8 is a perspective view of another embodiment of my new female hygiene apparatus with the cap in open position, it being understood that the only differences reside in the length and shape of the edge of the neck element and the circular shape in the center;

FIG. 9 is an elevational view of FIG. 8 on a reduced scale when hung in an upside down position.

The strap is shown broken away in FIG. 1,2,3,4,5,6,7, and 8 for convenience of illustration.

In FIG. 9, the broken line showing of a wall and hanger is for purposes of illustration only and forms no part of the claimed design.

In FIG. 9, the broken line showing of a wall and hanger is for purposes of illustration only and forms no part of the claimed design.
